MOP

Oscar Carlson, Minneapolis, Minn., assignor to
Reel-Mop Corporation, Minneapolis, Minn., a
corporation of Minnesota

Application April 8, 1932. Serial No. 603,935

6 Claims. (Cl. 15—120)

My present invention has for its object the provision of a simple and highly efficient mop.

To the above end the invention consists of the novel devices and combinations of devices herein-
5 after described and defined in the claims.

In the accompanying drawings, which illustrate the invention, like characters indicate like parts throughout the several views.

Referring to the drawings:

10 Fig. 1 is an elevation of the mop with a portion of its stick broken away and with some parts shown in different positions by means of broken lines;

15 Fig. 2 is an edge elevation of the parts shown in Fig. 1;

Fig. 3 is a view corresponding to Fig. 1 with the exception that the stick is positioned as indicated by broken lines and the swab twisted;

20 Fig. 4 is an elevation of the stick removed from the mop and with the upper end portion thereof broken away;

Fig. 5 is a perspective view of the head and clamp removed from the stick;

25 Fig. 6 is a fragmentary detail view with some parts sectioned on the line 6—6 of Fig. 1, on an enlarged scale.

Fig. 7 is a fragmentary detail view with some parts sectioned on the line 7—7 of Fig. 1, on an enlarged scale;

30 Fig. 8 is a detail view partly in plan and partly in section taken on the line 8—8 of Fig. 2; and

Fig. 9 is a perspective view of the swab removed from the mop.

The improved mop includes a stick or handle 10, a head 11, a swab clamp 12, and a swab 13. Fixed on the inner end of the stick 10 is a T-head 14 and formed in said stick is a pair of annular lock-grooves 15 and 16 spaced longitudinally thereof. The head 11 is in the form of a sleeve 40 through which the stick 10 extends with freedom for endwise sliding movement and for turning movement about the longitudinal axis of said stick.

Applied to the upper end portion of the head 45 11 is a corrugated hand grip 17 of rubber or any other suitable material and by which the head 11 is held while sliding the same longitudinally on the stick 10 or while turning the same thereon.

The swab clamp 12 includes a pair of fixed arms 50 18 and a pair of cooperating relatively movable arms 19. Said fixed arms 18 are integral with the lower end of the head 11 at diametrically opposite points and extend radially therefrom in longitudinal alignment. Eyes 20 and 21 are formed in the outer ends of the arms 18 by folding said arms downward and inward upon themselves. The two movable arms 19 are parallel and are formed from a single spring rod folded upon itself and laterally spaced. The transverse 55 connection between the two arms 19 affords a

hinged member 22 which extends through the eye 20 and hingedly connects said arms to the respective arm 18 for swinging movement toward or from the arms 18.

To releasably hold the arms 19 in operative relation to the clamping arms 18 they are provided at their free ends with lock fingers 23 which extend endwise into the eye 21 from opposite ends thereof. These lock fingers 23 are formed by bending the outer end portion of the arms 19 laterally inward. To remove the fingers 23 from the eye 21 or insert the same therein it is only necessary to spring the arms 19 laterally away from each other.

The spring arms 19 also perform another important function in that they cooperate with either lock-groove 15 or 16 to hold the head 11 on the stick 10 in predetermined adjustments. The diameter of the stick 10 is such as to hold the arms 19 spread apart when out of the grooves 15 and 16 so that when said arms are brought into registration with either one thereof they will snap into the respective groove and thereby hold the stick 10 and head 11 against relative longitudinal movement. A pull on the stick 10 and the head 11 in opposite directions will cause the arms 19 to be cammed out of the lock-groove 15 or 16 with which they are interlocked. The lock-groove 15 is closely positioned to the T-head 14 and the lock-groove 16 is positioned a distance 80 outward of the T-head 14 which is substantially equal to the length of the swab 13, as will presently appear.

The swab 13, as shown, is of the knitted type, 95 is substantially flat and its length is considerably longer than its width. This swab 13 is folded upon itself and provided at the free ends of its two plies with a hem 24 preferably formed from a single piece of canvas or other suitable material and secured thereto by stitches X. The purpose of this hem 24 is to provide simple and efficient means for detachably securing the swab 13 to the head 11 by means of the clamp 12. It 100 will be noted that the arms 19 extend longitudinally through the hem 24 and with said hem 105 squeezed between the arms 18 and 19. The stick 10 extends through a hole 25 in the hem 24 and an opening 26 between the free ends of the two plies of the swab 13, see Fig. 6.

When the swab 13 is used as a mop the stick 110 10 is retracted with respect to the head 11 and said stick and head held against relatively longitudinal movement by the arms 19 and cooperating lock-groove 15. In this position of the head 11 on the stick 10 the T-head 14 is in the opening 115 26 and by its engagement with the two plies of the swab 13 prevents the connected end of said swab from turning about the longitudinal axis of the stick 10. It will thus be seen that the arms 19, cooperating lock-groove 15 and the T- 120

head 14, substantially, rigidly connect the stick 10, the head 11 and the swab 13 so that said swab may be controlled by the stick 10 during mopping action.

5 To wring water from the swab 13 the stick 10 is projected through the head 11 until its T-head is brought into engagement with the closed outer end of the swab 13. In this adjustment of the head 11 on the stick 10 the arms 19 will snap 10 into the lock-groove 16 and hold said stick and head against relative longitudinal movement. With the stick 10 thus adjusted with respect to the head 11 the operator grips the stick 10 in one hand and the hand grip 17 in the other and 15 then turns the same in opposite directions, thus twisting the swab 13 about the stick 10 which produces a wringing action on the swab 13. During this twisting of the swab 13 about the stick 10 the inner end thereof is held by the clamp 12 to turn with the head 11 and the outer end of said swab is held by the T-head 14 to turn with the stick 10.

When wringing the swab 13 the stick 10 and the head 11 are held against relative longitudinal movement by the clamping arms 19 and lock-groove 16, as previously stated, which causes the swab 13 to stretch and thereby assist in wringing the mop 13. Obviously, the annular lock-groove 16 permits the arms 19 to turn therein during wringing action of the swab 13. As shown, the two plies of the swab 13 are connected at their longitudinal edge portions partway up from the closed outer end of said swab, as indicated at Y, to form a sort of a sack which prevents edge-wise displacement of the swab 13 on the T-head 14.

Another important function of the mop is that the swab 13 may be used as a duster. In this use of the swab 13 the stick 10 and head 11 have the same relative adjustment as when holding the swab 13 for wringing action, or in other words, the stick 10 is projected with respect to the head 11 to stretch the swab between the head 11 and the T-head 14. In this adjustment of the stick 10 and head 11 the swab 13 is held flat transversely thereof by the clamp 12 and the T-head 14. When the swab 13 is used as a duster the stick 10 and head 11 are held against relative longitudinal movement by the clamping arms 19 and the cooperating lock-groove 16.

To apply the swab 13 to the head 11 the fingers 23 are first released from the eye 21 and the clamping arms 19 positioned, as shown in Fig. 5. Said arms 19 are then inserted endwise through the hem 24 and the fingers 23 again inserted into the eye 20 to hold the arms 19 in operative relation with respect to the arms 18 with the hem 24 clamped therebetween. The outer end of the stick 10 is then inserted between the plies of the swab 13, at one edge of said swab, through the opening 26, the hole 25, and the head 11. This endwise movement of the stick 10 is continued until the arms 19 snap into the lock-groove 15 and at which time the T-head 14 is positioned in the opening 26 so that the entire swab 13 is free for mopping action.

From the above description it is evident that the improved mop may be very quickly adjusted for use as a mop or as a duster or operated to 70 wring water from the swab.

The drawings illustrate a commercial form of

the invention, but it will be understood that the same is capable of certain modifications as to details of construction, arrangement and combinations of parts within the scope of the invention herein disclosed.

What I claim is:

1. A mop comprising a stick, a sleeve-like head mounted on the stick for longitudinal sliding movement and for turning movement thereon, and a swab-holding clamp including a pair of relatively fixed diametrically opposite radial arms on the head and a pair of cooperating relatively movable spring arms hingedly connected to one of said fixed arms and releasably secured to the other of said fixed arms with the stick extending therebetween.

2. The structure defined in claim 1 in which the diameter of the stick is such as to hold the spring arms sprung apart and under tension, and which structure further includes a pair of annular lock-grooves in the stick spaced longitudinally thereof and into which grooves the spring arms snap when brought into registration therewith to hold the stick and head against relative longitudinal movement but permit free relative turning movement of the stick and head.

3. The structure defined in claim 1 in which the diameter of the stick is such as to hold the spring arms sprung apart and under tension, and which structure further includes an annular lock 105 groove in the stick into which the spring arms will snap when brought into registration therewith to hold the stick and head against relative longitudinal movement.

4. A mop comprising a stick, a head mounted 110 on the stick for longitudinal sliding movement, a swab holding clamp including a spring arm extending transversely of the stick and having one of its ends hingedly attached to the clamp and its other end releasably attached thereto 115 and holding the arm in contact with the stick under tension, and a lock groove in the stick into which the arm will snap when brought into registration therewith during longitudinal sliding movement of the head on the stick.

5. A mop comprising a stick, a head mounted on the stick for longitudinal sliding movement, a swab holding clamp including a spring arm extending transversely of the stick and having one of its ends hingedly attached to the clamp and its other end releasably attached thereto and holding the arm in contact with the stick under tension, and a pair of longitudinally spaced lock 130 notches in the stick into either one of which the spring arm will snap when brought into registration therewith during longitudinal sliding movement of the head on the stick.

6. A mop comprising a stick, a head mounted on the stick for longitudinal sliding movement, a swab holding clamp including a pair of spring 135 arms extending transversely of the stick on opposite sides thereof, said arms having one of their ends hingedly attached to the clamp and their other ends releasably attached thereto and holding the arms in contact with the stick under tension, and a lock groove in the stick into which the arms will snap when brought into registration therewith during longitudinal sliding movement of the head on the stick.
